(57) **CLAIM**

The ornamental design for a stacked iron core of a generator, as shown and described.

DESCRIPTION

FIG. 1 is a top plan view of a stacked iron core of a generator showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a perspective view thereof; and,

FIG. 8 is an enlarged, partial front elevational view of the region defined by lines 8-8 of FIG. 3.
